UNITED STATES PATENT OFFICE

NEAL T. MCKEE, OF BRONXVILLE, NEW YORK, ASSIGNOR TO THE SUPERHEATER COMPANY, OF NEW YORK, N. Y.

EXHAUST-STEAM INJECTOR

Application filed March 3, 1927. Serial No. 172,367.

My invention relates to exhaust steam injectors of the type in which the primary operating fluid is exhaust steam from a locomotive engine, and which may be operated 5 by live steam, when exhaust steam is not available, by live steam throttled to approximately exhaust steam pressure, such as is disclosed in U. S. Patent No. 1,531,004, granted March 24, 1925, to Malcolm Hard, et al.

- 10 In injectors of this type, a relatively small quantity of high pressure live steam, herein-after referred to as "supplementary steam", is generally used, both when the injector is operating on exhaust steam and when it is being 15 operated by low pressure live steam, which will hereinafter be referred to as "auxiliary steam". Numerous control systems have been developed for bringing the control of the several steam supplies, as well as the water 20 supply, to the injector, under the control of the operator through the medium of a main control valve, but in these prior systems, the amount of supplementary steam supplied to the injector has been a fixed quantity and in 25 such prior systems, one or more of the steam supplies has been permitted to reach the injector, when the latter is started, before water is supplied thereto. Such prior systems, further, have been arranged so that a plurality 30 of steam conduits has been required to carry the live steam used for operating the injector from the control valve, located in or near the engine cab, and the injector, which is located some distance therefrom.
- 35 The present invention relates specifically to a system for controlling the exhaust steam, supplementary live steam and auxiliary live steam, and the water which is supplied to the injector, and the primary object 40 of the invention is the provision of a simplified control system, whereby the operating steam supplied to the injector may be conducted thereto through a single conduit leading from the main control valve.
- 45 A further object of the invention is the provision of a control system in which the water valve is opened by means actuated by the live steam entering the injector, this means being so arranged that no live steam can reach the 50 injector until after the water valve has been
- opened. A still further object of the invention is the provision of an exhaust steam control valve, which is opened by the pressure of live steam which has passed the water valve actuating means, this arrangement insuring that the exhaust valve is closed until after the water valve is opened. By means of this arrangement of the control system, water is allowed to reach the injector before steam of any character is admitted thereto, 60 and the action of the water in cooling the injector nozzles before steam is admitted thereto assists in the rapid establishment of a jet upon starting the injector.
- 65 Another object of the invention is the provision of means for regulating the flow of supplementary live steam to the injector, such means being so arranged that the variation in the amount of supplementary steam permitted to flow to the injector in no way affects 70 the control of the water supply, the auxiliary steam supply or the exhaust steam supply.
- 75 Further and more detailed objects of the invention as well as the advantages to be derived through the use of my invention will become apparent as the following detailed description of a specific embodiment thereof proceeds:
- 80 In the accompanying drawings, Fig. 1 is a fragmentary section, taken through an injector constructed in accordance with my invention, said section being taken along the line 1-1 of Fig. 3; Fig. 2 is a fragmentary section, taken along the line 2-2 of Fig. 3, and Fig. 3 is a schematic representation of the entire control system, in which the valve mechanisms controlling the live steam and water supplies to the injector have been broken away from the main body thereof, in order that the entire control system 85 may be shown with all of the several elements thereof in their proper functional relation. Fig. 3 is included in order to facilitate a ready understanding of the invention, and it is to be understood that this figure is diagrammatically, rather than constructionally, accurate, the relation of the several elements and their connecting passages being as shown in Figs. 1 and 2.
- 90 The injector proper, indicated generally

at "A" is controlled through the medium of the manually operable valve "B", which controls the entire live steam supply leading to the injector, as well as the exhaust steam supply and the water supply. An automatic valve "C" controls the alternate admission of exhaust steam or auxiliary live steam to the injector and said automatic valve is governed by live steam taken from the engine supply line, and carried to the automatic valve through a conduit in which is located the intercepting valve "D", associated with the main control valve.

The injector "A" is of the usual and well-known form in which a housing 1 forms a low-pressure steam chamber or cavity 2 to which exhaust steam is supplied through inlet 3 controlled by the exhaust valve 4 and to which auxiliary steam is also admitted when exhaust steam is not available through the passage 5 and ports 6. Exhaust, or auxiliary, steam, as the case may be, is delivered from chamber 2 to the main steam nozzle 7, in which is centrally located the steam nozzle 8, supplied with supplementary high pressure steam through the passage 9. Steam delivered through nozzle 7 combines with water supplied through chamber 10, in the water nozzle or cone 11, from which it passes through a secondary low-pressure steam nozzle 12 to the combining and delivery tubes of the injector (not shown). The exhaust valve 4, controlling the inlet 3 is opened by means of the fluid pressure actuated piston 13, located within the cylinder 14 carried by the injector housing, the latter also forming a passage 15 leading from the cylinder 14 through the chamber 2. The valve 4 is moved to closed position by the spring 16, the closing action of which is supplemented by the pressure of exhaust steam admitted through inlet 3.

As the injector structure just briefly described is of a well-known form, a further detailed description of the constructional features thereof is not deemed necessary to an understanding of the present invention.

The main control valve "B" which, when the injector is applied to a locomotive, is located in or adjacent the cab thereof, comprises a housing 16 formed with an inlet 17 to which live steam is delivered at boiler pressure from the turret of the locomotive. The housing 16 forms a pair of steam chambers, 18 and 19, the former in communication with the live steam inlet 17 and the latter in communication with the live steam conduit 20 leading to the injector. Chambers 18 and 19 are connected by a port 21, the circumference 65 of which forms a valve seat against which the single main control valve 22 seats to close the port and thereby shut off all live steam to the injector. Valve 22 is provided with an elongated stem 23 passing through a suitable stuffing box 24 to the exterior of

the housing 16 where it is connected to a suitable control lever 25, by means of which the main control valve 22 is manually opened or closed. A second port 26 is formed in the housing 16 in alignment with port 21, and this port is controlled by valve 27, which is attached by means of a lost motion connection to an extension 28 of the valve 22, said extension passing through port 21. The port 26 provides communication between the chamber 19 and the intercepting valve, which will be described in detail hereinafter.

The live steam conduit 20, as previously pointed out, leads from the main control valve to the injector, and my invention permits the substitution of a single conduit for carrying the entire live steam supply, in place of separate conduits which have heretofore been used for carrying the auxiliary and supplementary steam supplies to the injector.

The steam supply conduit 20 is attached to the injector near the water valve actuating means. The water valve is mounted in a housing 29, which in Fig. 1 has been shown as cast integral with the injector housing 1. Obviously, this portion of the housing may equally well be a separate casing bolted to the side of the injector and, as indicated in Fig. 3, the housing 29 is a separate element which, however, forms a unitary assembly with the main body of the injector.

Referring now to Fig. 3, it will be seen that the housing 29 forms a water inlet chamber 30 to which water is admitted from a suitable source of supply (not shown), and an outlet passage 31 leading to the water chamber 10 of the injector, the connection being shown in the diagrammatic representation in Fig. 3 by way of conduit 32. Chamber 30 and passage 31 are connected by a port 33, the circumference of which forms a valve seat against which the water valve 34 seats to shut off the water supply to the injector. Valve 34 is provided on its upper face with an annular rib for the retention of a spring 35 held in a suitable housing cap 36 and serving to urge the water valve 34 to closed position. The bottom of the water valve housing 29 forms a steam chamber 37 in communication with the conduit 20 and the chamber 37 is placed in communication with a second steam chamber 38 by a port 39 in alignment with port 33. The steam chamber 38 is separated from the water passage 31 by a web which forms a valve stem guide 40 in alignment with ports 33 and 39, and which has an open-ended cylindrical recess 41, formed below the guide 40. Valve 34 is provided with a downwardly extending stem 42, which passes through guide 40 and has attached to its lower end a piston 43 which, when valve 34 is seated, is located in the port 39. The piston 43 is made a sliding fit in port 39 and as will be obvious from the figure, the latter port is closed when the water valve is in its closed position. On its

100
105
110
115
120
125
130

upper face, piston 43 is provided with a circular seat 43^a, which abuts against a corresponding seat 41^a when the piston is raised to its upper position within the recess 41.

The automatic valve "C" is provided for the purpose of automatically shifting the injector from live steam to exhaust steam operation, or vice-versa, and in the present instance the automatic valve has been shown as located in an extension of the housing 29 which, as previously pointed out, may be either integral with the main housing 1 or a separate casing assembled therewith. The automatic valve portion of the housing 29 comprises three aligned chambers, 44, 45 and 46, chambers 44 and 45 being connected by port 47 and chambers 45 and 46 being connected by port 48, the latter being in alignment with port 47. Chamber 44 is surrounded by a lateral extension 38^a of the chamber 38, with which it is placed in communication by means of the small port 49 which will hereinafter be referred to as a "choke". An outlet 50 is provided at the bottom of chamber 44 which serves to provide communication between this chamber and the auxiliary steam passage 5 in the injector by way of the passage 51. The passage 51 is shown in the diagrammatic representation of Fig. 3 as a separate conduit which, obviously, is not required in the actual injector, as shown in Fig. 1.

The lateral extension 38^a of chamber 38 is provided with a suitable outlet 52, leading to the passage 53 and serving to provide communication between the chamber 38 and the supplementary steam passage 9 in the injector proper. This passage has been indicated in Fig. 3 by a conduit 53 similar to conduit 51. The size of the opening at outlet 52 is controlled by means of the manually adjustable needle valve 54, which extends through a suitable stuffing box 55 to the exterior of the housing.

The chamber 45 of the automatic valve housing is provided with an outlet connected by way of passage 56 with the passage 15 in the injector proper, and this passage has also been represented in Fig. 3 by a separate conduit 56.

The automatic valve "C" comprises a main valve member 57 consisting of a lower head 58 located in chamber 44 and an upper piston 59 located in port 48 and connected with head 58 by means of a stem extending through the port 47 and considerably smaller in diameter than the latter. The valve head 58 is formed with oppositely disposed valve faces 58^a and 58^b, the former seating when the valve is in its lower position against a similar valve seat surrounding the outlet 50, and the latter when the valve is in its upper position, seating against a similar seat formed around the port 47. The piston 59 is a sliding fit in the port 48 and is sufficiently

loose so that an appreciable quantity of steam may pass between the piston and the wall of the port. A check valve 60, guided in the housing cap 61, is provided with an annular seat on its lower face, which cooperates with a similar seat formed in the bottom of chamber 46 around port 48. The upper face of piston 59 is extended so that when the automatic valve member is in its lower position, piston 59 will just clear the lower face of check valve 60 and allow the latter to seat. The clearance between piston 59 and valve 60, when the former is in its lower position and the latter seated, is so slight, however, that upon upward movement of the piston 59, the valve 60 is raised thereby and held in open position during the time when the automatic valve is in its upper position.

Chamber 46 is provided with an opening which is connected by means of a pipe 62 with the intercepting valve "D".

The intercepting valve "D" comprises a housing 63 attached to the main control valve housing 16 and forming a pair of chambers 64 and 65, the former in communication with chamber 19 by way of the valve controlled port 26 and the latter in communication with the chamber 46 of the automatic valve by way of the pipe 62. Chambers 64 and 65 are placed in communication by the port 66 around which there is formed within the chamber 65 a valve seat. At the opposite end of chamber 65 there is provided a steam inlet connected by means of pipe 67 with the supply pipe or valve chest of the engine from which the injector is supplied with exhaust steam, and this inlet is provided with a valve seat disposed in the chamber 65 opposite the valve seat surrounding port 66. Chamber 64 is provided with an atmospheric vent pipe 68 entering the chamber adjacent the port 66.

The intercepting valve member 69 comprises a valve head 70 located in chamber 65 and provided with oppositely disposed valve faces 70^a and 70^b and adapted to move to seat against one or the other of the corresponding valve seats provided in chamber 65 to close port 66 or the live steam inlet 67.

The valve head 70 is connected to a suitably packed piston 71 slidably mounted in the cylindrical chamber 64 between port 26 and vent 68 by a valve stem passing through port 66, said stem being considerably smaller in diameter than the port.

In the position as shown in Fig. 3 the injector is shut off with the main control valve 22, the water valve 34 and the exhaust steam valve 4 in closed position.

Assuming that the engine is running and exhaust steam is available, the operation is as follows: The control handle 25 is opened to lift the control valve 22 from its seat and it will be noted that the first opening movement permits the lifting of valve 22 without moving the valve 27 away from its seat

around the port 26, because of the lost motion connection between the two valves. Moreover, the valve 27 is positively held to its seat by steam admitted to the chamber 19 upon the opening of valve 22, and the valve 27 remains seated until the control lever is pulled past the position indicated as open position, when it is pulled from its seat as the control lever is moved to the emergency 10 position, which will be described later.

When the control valve 22 is lifted from its seat, live steam from the locomotive boiler is admitted through conduit 20 to chamber 37 under piston 43 which, when in the position shown, with the water valve closed, positively prevents the passage of any appreciable quantity of steam to the injector. The steam pressure built up in chamber 37 acts on piston 43 to overcome the spring 35 and forces the piston into the cylindrical recess 41, in which position of the piston the faces 43^a and 41^a form a steam-tight joint preventing the leakage of steam through the guide 40 into the water passage 31. This 25 action raises water valve 34 and permits water to flow to the injector prior to the entrance of steam thereinto. This sequence of admission aids in rapid establishment of the jet, as the first fluid entering the injector is 30 the cold water rather than steam, which, if allowed to enter the injector first, would tend to warm the latter and hinder the rapid condensation necessary to the quick establishment of a jet. After having forced the 35 piston 43 to its upper position, the live steam supply is free to flow through port 39 into chamber 38, from whence it flows to the high pressure supplementary steam jet 8 of the injector by way of the lateral extension 38^a 40 of chamber 38, the port 52, passage 53 and steam passage 9. Live steam is also free to flow through the choke port 49 into the lower chamber 44 of the automatic valve.

Under the conditions assumed, live steam 45 from the engine supply flows through pipe 67 into the intercepting valve chamber 65, and forces the intercepting valve member 70 to its seat around port 66, whereby the 50 escape of live steam to the atmosphere through vent 68 is prevented. With the intercepting valve in this position, the live steam supply entering through pipe 67 flows through the pipe 62 into the upper chamber 46 of the automatic valve and holds the 55 check valve 60 on its seat surrounding the port 48. With the check valve in this position, the automatic valve member is held downward far enough so that the valve face 60 58^b is unseated.

Live steam entering the chamber 44 by way of port 49 is free to flow through the port 47 into the chamber 45 and also to leak past the loose piston 59 into the space above 65 the piston and below check valve 60, where

it is trapped by the latter valve, which is retained on its seat by the live steam pressure thereabove in chamber 46. The dimensions of the automatic valve head 58 and the piston 59 are such that under these conditions, the automatic valve is forced by steam pressure to its lower position, where the valve face 58^a is seated to close the outlet 50 leading to the auxiliary steam passage 5 of the injector.

With the automatic valve in this position, steam is free to flow from the chamber 45 by way of the passage 56 to the steam passage 15 in the injector, from whence it is admitted to cylinder 14 to actuate piston 13 and open the exhaust steam valve 4.

From the foregoing it will readily be apparent that under the conditions assumed, the opening of the control valve 22 will start the injector by first admitting water thereto 85 and thereafter substantially simultaneously admitting both supplementary and exhaust steam for the purpose of establishing a jet.

If, when the injector is operating on exhaust steam, the engine throttle is closed, the injector is automatically shifted to live steam operation by the action of the automatic valve, which operates as follows: When the engine is shut off, the live steam pressure holding the check valve 60 to its seat is relieved by the absence of steam in the supply pipes 67 and 62, and the pressure built up under valve 60 by leakage past piston 59 operates to lift the valve from its seat and relieve the pressure existing on the top of piston 59. Under this condition the live steam pressure acting on the underside of piston 59 and also on the under face of the valve head 58 outside the seat 58^a is sufficient to overcome the pressure exerted on the upper face of the valve head 58, and the automatic valve is shifted to its upper position in which the valve face 58^b is seated against the wall surrounding port 57 to close the latter, and the valve face 58^a is unseated to open port 50 105 and admit auxiliary steam to the low pressure steam chamber 2 of the injector by way of passages 51 and 15 and ports 6. The closure of port 47 shuts off the steam supply to the exhaust valve actuating piston 13 and the exhaust valve is closed by the action of spring 16, the pressure existing in the passages 15 and 56 being dissipated by leakage past piston 59 and valve 60 to the pipe 62. With the 110 automatic valve in its upper position and the injector operating on live steam, a large quantity of steam is supplied to the injector through the port 49, which is made sufficiently small to exert a throttling effect, whereby live steam passes into the chamber 44 and 115 on to the injector at a substantially reduced pressure, where it performs the same function as the low pressure exhaust steam. It will be noted that as soon as the automatic 120 valve is lifted from its lower seat the area 125

acted upon by steam pressure tending to hold the valve in its upper position is increased by the area encompassed by said seat, and the reduction of the steam pressure in chamber 44 under these conditions is necessary in order that the automatic valve may again be shifted to its lower position by the admission of steam to chamber 46.

If the injector is being operated wholly on live steam and the engine throttle is opened, the injector is immediately shifted to exhaust steam operation by the automatic valve due to the admission of live steam to chamber 46 through pipes 67 and 62 leading from the engine supply pipe. This steam at high pressure acts first on the upper face of piston 59, as the check valve 60 is lifted from its seat, and is sufficient to force the automatic valve to its lower position against the pressure exerted by the low pressure steam in chamber 44. After the automatic valve has been shifted to its lower position, the check valve 60 is free to drop to its seat against which it is thereafter held by the live steam pressure in chamber 46.

If the injector is started when the engine is not running, the automatic valve is immediately forced to its upper position by the admission of steam to the chamber 44, as, under these conditions, there is no pressure existing in the chamber 46.

Under some conditions it is desirable to operate the injector on live steam even though the engine is running and exhaust steam is available, and in order to permit this the intercepting valve is provided, the operation of which is as follows: The operating lever 25 is in this case pulled past the normal open position to the emergency position, and this action lifts the valve 27 from its seat and permits live steam to enter the chamber 64 and act on piston 71, moving it to the right. The movement of piston 71 shifts the valve member 70 to a position where face 70^a shuts off the live steam supply from pipe 67 and unseats the valve face 70^b to place the pipe 62 in communication with the atmosphere by way of port 66 and vent 68. This operates to relieve the pressure in chamber 46 and permits the automatic valve to shift to live steam operating position in the same manner as if the engine had been shut off.

The amount of supplementary live steam required is less if the inlet water temperature is low than if it is high and the temperature variation of the inlet water is sufficient, between summer and winter operation, to make a material difference in the amount of supplementary steam required. By the provision of the adjustable valve 54 in the supplementary steam passage, the quantity of supplementary steam used may be regulated without affecting the admission of the other operating flues and in this manner the most

economical operation of the injector may be secured.

The quantity of supplementary steam required is also dependent upon the pressure at which exhaust steam is available, and as different engines to which the same type of injector may be applied operate at different average exhaust pressures, this adjustment is valuable in setting the supplementary steam supply on any particular engine. In some cases, where the engine exhaust pressure is high and the inlet water temperature is very low, it is possible to operate the injector without the use of supplementary steam, and this adjustment further permits the shutting off of the supplementary steam entirely in such cases, without affecting the control or operation of the injector.

From the foregoing description, it will be apparent that by my invention I have provided a control system in which the entire operating mechanism with the exception of the main control valve and the intercepting valve is located at the injector which results in a piping arrangement considerably simpler than those heretofore required, and that I have, further, provided a control system which will assure the most rapid and efficient starting of the injector and which permits of the adjustment of the live steam supply for the most economical operation of the injector.

It will further be apparent that many changes and variations in the form and arrangement of the several elements shown may be made without departing from the spirit of the invention which is to be understood as embracing all constructions which may fall within the scope of the appended claims.

What I claim is:

1. An exhaust steam injector control system of the type wherein a main control valve located at a point remote from the injector governs the admission of live steam to a plurality of fluid pressure actuated valves for admitting water, exhaust steam, and live steam to the injector, said valves including an automatic valve governing the admission of auxiliary live steam to the injector, characterized by the provision of a single conduit leading from said main control valve and terminating at said injector for supplying live steam to operate both the injector and said valves, a branch conduit leading from said single conduit for supplying supplementary live steam to the injector, a manually adjustable valve located in said branch conduit, a second branch conduit controlled by said automatic valve leading from said single conduit to the injector, and a third branch conduit leading from said single conduit to the fluid pressure actuated valve controlling the admission of exhaust steam.

2. The combination with an injector to

which water, exhaust steam, auxiliary live steam and supplementary live steam are admitted, of a water valve and fluid pressure actuating means therefor, and an automatic valve for controlling the admission of the auxiliary live steam and exhaust steam in alternation to said injector, said water valve and automatic valve being connected with said injector and forming a unitary assembly therewith, a main control valve located at a point remote from said injector and connected with a source of live steam, a single conduit leading from said main control valve and in communication with the actuating means for said water valve, and a connection leading from said water valve actuating means to said automatic valve.

3. The combination with an injector to which water, exhaust steam, auxiliary live steam and supplementary live steam are admitted, of a water valve and fluid pressure actuating means therefor, an automatic valve for controlling the admission of the auxiliary live and exhaust steam in alternation to said injector, said water valve and automatic valve being connected with said injector and forming a unitary assembly therewith, a main control valve located at a point remote from said injector and connected with a source of live steam, a single conduit having one end connected with said main control valve and terminating at its other end adjacent to and in communication with the actuating means for said water valve, and an auxiliary steam conduit leading from said single conduit to the injector through said automatic valve.

4. The combination with an exhaust steam injector having a main steam nozzle, a supplementary steam nozzle and a water valve, of fluid pressure actuating means for operating said water valve, a main control valve located at a point remote from said injector and connected with a source of live steam, a single conduit leading from said main control valve to said fluid pressure means, conduits leading from said means to said main and supplementary nozzles, and an automatic valve located in the conduit leading to said main nozzle for preventing the flow of live steam therethrough when exhaust steam is available for operating said injector.

5. The combination with an injector to which water, exhaust steam, auxiliary live steam and supplementary live steam are admitted, of a main control valve located at a point remote from the injector and connected with a source of live steam, a single conduit leading from said main control valve and terminating in juxtaposition to said injector, a casing associated with said injector to form therewith an unitary assembly, said casing being provided with a pair of passages, one for supplying the supplementary live steam to said injector and the other for supplying auxiliary live steam, a water valve and fluid

pressure actuating pressure means therefor, said means being located in said single conduit and preventing flow of steam therethrough until said water valve is opened, and an automatic valve interposed in said auxiliary live steam passage between said single conduit and the injector for controlling the admission of auxiliary live steam to said injector.

6. The combination with an injector to which water, exhaust steam, auxiliary live steam and supplementary live steam are admitted, and a water valve for controlling the admission of water to said injector, of a main control valve located at a point remote from said injector, a single conduit leading from said main control valve and terminating closely adjacent to said injector, fluid pressure actuated means operatively associated with said water valve located at the exit of said conduit to be actuated by the live steam flowing therethrough, and a plurality of branch conduits in communication through said fluid pressure actuated means with said single conduit, one of said branch conduits serving to supply supplementary live steam to the injector, a second of said branch conduits serving to supply auxiliary live steam to said injector, a valve for admitting exhaust steam to said injector and fluid pressure actuated means therefor, a third one of said branch conduits being connected with the fluid pressure actuated means for said exhaust valve, and an automatic valve for controlling the admission of steam in alternation through said second and said third branch conduits, interposed between said single conduit and said last named branch conduits.

7. The combination with an injector to which water, exhaust steam, auxiliary live steam and supplementary live steam are admitted, of a main control valve located at a point remote from said injector and connected with a source of live steam, an automatic valve located in juxtaposition to said injector, a single conduit under the control of said main control valve for admitting live steam to said automatic valve, a water valve for controlling the admission of water to said injector, and fluid pressure actuating means associated therewith, said fluid pressure actuating means being located within said single conduit and between said control valve and said automatic valve.

8. An exhaust steam injector control system of the type wherein a plurality of fluid pressure actuated valves are provided for controlling the admission of water, exhaust steam and live steam to the injector, a single manually operated main control valve located at a point remote from said injector is provided for admitting live steam to said valves and an automatic valve is provided for governing the admission of exhaust steam and auxiliary live steam in alternation, char-

acterized by said automatic valve being associated directly with the injector to form an unitary assembly therewith, the provision of a single conduit for connecting said automatic valve and said main control valve, and the interposition of the fluid pressure actuated means for said water valve in said single conduit between said main control valve and said automatic valve.

9. The combination with an injector to which water, live steam and exhaust steam are admitted, of a main control valve connected with a source of live steam, a single conduit for the entire live steam supply, said conduit leading from said control valve to said injector, a water valve and fluid pressure actuating means therefor, said means being located in said single conduit and preventing flow of steam therethrough until said water valve is opened.

10. The combination according to claim 9 in which said water valve actuating means comprises a piston closing said conduit when the water valve is closed, and movable by the pressure of steam admitted through the main control valve to open simultaneously the water valve and the conduit.

11. The combination with an injector to which water, supplementary live steam, auxiliary live steam, and exhaust steam are admitted, of a main control valve located at a point remote from the injector and connected with a source of live steam, a conduit connected with said main control valve for supplying auxiliary live steam to the injector, an automatic valve within said conduit for controlling the admission of auxiliary live steam and exhaust steam in alternation to said injector, a conduit for supplying supplementary live steam connected with said main control valve, and a valve located in the supplementary live steam conduit between said main control valve and the injector for controlling the flow of steam through said supplementary live steam conduit independently of the flow to the auxiliary live steam conduit.

12. The combination with an injector to which water, supplementary live steam; auxiliary live steam, and exhaust steam are admitted, of a main control valve located at a point remote from the injector and connected with a source of live steam, a conduit connected with said main control valve for supplying auxiliary live steam to the injector, an automatic valve within said conduit for controlling the admission of auxiliary live steam and exhaust steam in alternation to said injector, a conduit for supplying supplementary live steam connected with said main control valve, a water valve and fluid pressure actuating means therefor under the control of live steam from said main control valve, and a valve in said supplementary live steam conduit between said main control valve and the injector for controlling the flow

of steam through said supplementary live steam conduit independently of the flow to the auxiliary live steam conduit and the water valve actuating means.

13. The combination with an injector to which water, exhaust steam, auxiliary live steam, and supplementary live steam are admitted, of a main control valve located at a point remote from said injector and connected with a source of live steam, a single conduit having one end connected with said main control valve and terminating in juxtaposition to said injector, a pair of conduits in communication with said single conduit for supplying supplementary and auxiliary live steam to said injector, a water valve and fluid pressure actuating means therefor, said fluid pressure actuating means preventing flow of steam to said pair of conduits until said water valve is opened.
